UNITED STATES PATENT OFFICE.

CHARLES FLECK, OF CLEVELAND, OHIO.

COLLAPSIBLE LANTERN OR SHADE.

932,772.

Specification of Letters Patent. Patented Aug. 31, 1909.

Application filed March 22, 1909. Serial No. 484,898.

To all whom it may concern:

Be it known that I, CHARLES FLECK, a citizen of the United States, residing at Cleveland, in the county of Cuyahoga and 5 State of Ohio, have invented certain new and useful Improvements in Collapsible Lanterns or Shades, of which the following is a specification.

My invention relates to improvements in 10 collapsible lanterns or shades, the primary object of the invention being to provide a generally improved device of this class which will be exceedingly simple in construction, cheap of manufacture, efficient in use, and 15 much better adapted to its intended purposes than any other device of the same class with which I am acquainted.

An object of the invention is to provide a 20 lantern or shade of light weight ornamental material capable of assuming various forms when set up, and adapted to be collapsed or knocked down so as to occupy but little space in transportation or storage and reducing the liability of breakage to a minimum.

25 With the above mentioned objects in view, the invention consists in the novel construction, arrangement, and combination of parts, hereinafter described, illustrated in one of its embodiments in the accompanying drawings, and particularly pointed out in the appended claims.

Referring to the drawings forming a part 30 of this specification, Figure 1, is a perspective view of the improved collapsible lantern or shade set up in the form of a lantern. Fig. 2, a top plan view of the same in its collapsed or knock down position. Fig. 3, a perspective view of the same in the form of a double walled dome or shade. Fig. 4, a 35 plan view of a metal blank preparatory to being formed into a panel-frame for containing and securing the transparent shading material. Fig. 5, a similar view of one of the base supporting section blanks. Fig. 45 6, a detail perspective view of one of the diagonally disposed reinforcing members of the panel-frames.

Similar characters of reference designate 50 like parts throughout all the figures of the drawings.

As illustrated in the accompanying drawings, the invention comprises pyramid frustums A and B, consisting of a series of hingedly connected trapezoidal panels and 55 upper base sections hingedly connected thereto. It will be observed that when used as a

lantern that the pyramid frustum B, is inverted as shown in Fig. 1.

The upper base sections of the pyramid frustums A, and B, form the top and bottom 60 supporting sections 1, and 2, respectively, said sections, in the present instance, being hexagonal in shape or outline and are provided about their peripheries with hinge-tabs or members 3, bent about a wire or bar 65 to form a hinge pintle for hingedly connecting the same to the trapezoidal panels of the pyramid frustums as hereinafter described. The top section 1, is preferably provided with an opening 4, and a carrying or sus- 70 taining bail member or handle 5.

The trapezoidal panels are hingedly connected to each other at the lower or coincident base portions of the frustums, preferably, by means of hinge tabs or members 6, 75 inclosing a wire or pintle, and to the top and bottom supporting sections 1, by means of hinge tabs or members 7, inclosing the hinge pintle carried by the hinge tabs 3, of said top and bottom sections. The frames 8, of the 80 panels are preferably formed of a very light thin metallic material and may be blanked out substantially as indicated in Fig. 4, providing an opening for receiving and containing suitable transparent shading material, 85 with marginal side wings 8^a, adapted to be bent, as indicated by the dotted lines in Fig. 4, of the drawings, to embrace the adjacent marginal edges of the shading material carried by the panel frames on the rear 90 or inner sides of the latter. The shading material may comprise any suitable and convenient substance and is preferably mounted in the form of two parts or panels 9, and 10, of different colored material such as colored 95 gelatin, or the like, and supported and reinforced at the meeting edges thereof by means of a diagonally disposed member 11, preferably longitudinally folded or crimped as shown in Fig. 6, to provide receiving grooves 100 11^a, for receiving and containing the adjacent marginal edges of the panels 9, and 10.

When the lantern or shade is lifted from its collapsed or knock down position as indicated in Fig. 2, by means of the bail member 105 or handle 5, the parts will assume the lantern form shown in Fig. 1, the marginal side edges engaging each other at the lateral edges of the frustums as shown. The lantern form shown in Fig. 1, may be used 110 either as a hand or suspended lantern inclosing a candle or other suitable source of

illumination and may be suitably supported upon a gas or electric light fixture, inclosing a gas incandescent bulb, or the like.

When the lantern is rested or deposited on its bottom section the top and bottom sections will approach each other causing the intermediate hinged portions of the panels to be expanded whereby the panels of the frustums will be folded upon each other in radially-extending panels as indicated in Fig. 2, of the drawings.

If the bottom section is elevated from the position shown in Fig. 2, it will carry with it the superposed top section and the radially-extending double walled panels will drop downwardly at the sides assuming its dome or shade position shown in Fig. 3, and the bottom and top sections may be supported in this position in a well known manner.

Having thus described my invention, without having attempted to set forth all the forms in which it may be made, or all the modes of its use, what I claim and desire to secure by Letters Patent is,—

1. A collapsible lantern or shade, comprising top and bottom sections hingedly con-

nected to a series of interposed panels hingedly connected to each other by means of hinge tabs inclosing a hinge pintle, said panels having their lateral edges engaging each other when said bottom section is suspended and each provided with parts of shading material supported and reinforced at the meeting edges thereof by an interposed bracing member.

2. In a collapsible lantern or shade, a pyramid frustum body consisting of an upper base section carrying a series of hingedly mounted truncated face panels having their sides abutting against each other at the lateral edges of the pyramid frustum when set up, each of said panels comprising a frame carrying a plurality of parts of shading material and an interposed reinforcing member having grooves containing the adjacent marginal edges of said parts.

In testimony whereof I have affixed my signature, in presence of two witnesses.

CHARLES FLECK.
